US00D360035S

United States Patent [19]

Miller et al.

[11] Patent Number: Des. 360,035

[45] Date of Patent: ** Jul. 4, 1995

[54] FLUID FLOW TRANSDUCER

[75] Inventors: Timothy A. Miller, Eagan; Thomas A. Anderson, New Hope, both of Minn.

[73] Assignee: Medtronic Inc., Minneapolis, Minn.

[**] Term: 14 Years

[21] Appl. No.: 18,240

[22] Filed: Feb. 2, 1994

[52] U.S. Cl. D24/187

[58] Field of Search .... D24/187; 73/861.12, 73/861.11, 861.13, 861.15, 194, 194 EM, 128/691, 661.08
